UNITED STATES PATENT OFFICE.

ROBERT L. COVINGTON, OF MORGANTOWN, WEST VIRGINIA.

TINNING-MACHINE.

1,341,495.

Specification of Letters Patent.

Patented May 25, 1920.

Application filed July 15, 1919. Serial No. 311,059.

To all whom it may concern:

Be it known that I, ROBERT L. COVINGTON, a citizen of the United States, residing at Morgantown, in the county of Monongalia 5 and State of West Virginia, have invented certain new and useful Improvements in Tinning-Machines; and I do hereby declare the following to be a full, clear, and exact description of the invention, such as will 10 enable others skilled in the art to which it appertains to make and use the same.

This invention relates to machines for applying tin plate to sheet metal and the primary object of the invention is to provide 15 an improved means for accurately regulating the tension on the rollers for engaging the sheet metal, so as to coat the sheet metal with the desired amount of tin.

A further object of the invention is to 20 provide means for engaging the rollers to normally hold the same in engagement with each other, said means having adjustable weights, which can be placed at different positions so as to accurately determine the 25 act pressure on the rollers for regulating the amount of tin metal coating on a sheet of metal being treated.

A further object of the invention is to provide V-toothed gearings or oblique toothed 30 gearings in lieu of the ordinary spur toothed gearings now in vogue for connecting and driving the rollers, so that uneven pressure and vibration on the plates as they pass through the rollers will be eliminated.

A still further object of the invention is 35 to provide an improved device of the above character, which is durable and efficient in use, one that is simple and easy to manufacture, and one that can be placed upon the 40 market at a reasonable cost.

With these and other objects in view, the invention consists in the novel construction, arrangement and formation of parts, as will be hereinafter more specifically described, 45 claimed and illustrated in the accompanying drawings forming a part thereof, in which:

Figure 1 is a transverse cross section through the tinning machine,

Fig. 2 is a fragmentary plan view of the 50 machine, parts of the same being shown in section,

Fig. 3 is a similar view, showing the V-toothed gearing for connecting the rolls,

Fig. 4 is a detail section through one of 55 the weights shown in Fig. 1,

Fig. 5 is a fragmentary plan view of the machine showing the opposite end thereof from that which is illustrated in Figs. 1 and 3,

Fig. 6 is a diagrammatic view showing the 60 arrangement of the driving gears carried by the rolls,

Fig. 7 is a diagrammatic view of the opposite ends of the rolls showing the connecting gears, and

Fig. 8 is a view in elevation of the roller mounting.

Referring to the drawings in detail, wherein similar reference characters designate corresponding parts throughout the several 70 views, the numeral 1 generally indicates the improved tinning machine which includes the tank 2, in which is adapted to be placed the tin coating 3. The tank 2 is of the ordinary or any preferred construction and receives the usual roller supporting frame 4, which is held in position by suitable brackets 5.

The roller carrying frame 4 includes the side plates 6, which slidably receive the bearings 7 for the rollers 8, which are arranged in superimposed pairs. The end plates 6 also carry the guides 9 for the sheet metal so as to guide the same through the rollers 8. As stated, the rollers 8 are mounted in superimposed pairs and are rotatably mounted in the bearings 7, which are slidably mounted in slots 10 formed in the end plates. The bearings 7 are provided with upper and lower flanges 11 for engaging the outer sides 80 of the plates 6 so as to prevent displacement of the bearings. The central portions of the walls of the slots are provided with inwardly extending lugs 12, which divide the pairs of rollers from each other. The rollers are provided with suitable adjustable brushes or scrapers 13, as is usual in the ordinary construction. The end plates carry downwardly extending slots 14, which are located at right angles to the slots 10 in which the bearings 85 7 are slidably mounted. Certain of the slots 14 communicate with the opposite ends of the upper and lower slots 10, while other of the slots 14 communicate with the inner ends of the upper and lower slots and all the slots 90 14 open out through the upper end of the plate, and these slots receive levers 15, 16, 17 and 18. The lever 15 is pivoted as at 19 intermediate its ends on a pivot pin 20, which is carried by the upper terminals of the ears 110

7 are slidably mounted. Certain of the slots 14 communicate with the opposite ends of the upper and lower slots 10, while other of the slots 14 communicate with the inner ends of the upper and lower slots and all the slots 105 14 open out through the upper end of the plate, and these slots receive levers 15, 16, 17 and 18. The lever 15 is pivoted as at 19 intermediate its ends on a pivot pin 20, which is carried by the upper terminals of the ears 110

21, carried by the upper surface of the end plate on each of the levers and the lever has its lower end provided with a right angularly positioned foot 22, which engages the 5 outer bearing 7 of one of the pairs of the upper rollers 8. The upper end of the lever is bent outwardly at right angles to provide the arms 24, which extend in a direction away from the rolls 8, and the same is provided with a series of graduations 25, with 10 which is adapted to coöperate a sliding weight 26 mounted on the arms. The lower end of the lever 16 is provided with a foot 27, which engages the inner roll of the other 15 upper pair of the rolls 8 and this lever is pivotally mounted as at 28 intermediate its ends to a pair of upstanding ears 29 formed on the upper surface of the plate. The upper end of the lever 15 is bent outwardly in the same 20 direction as the upper end of the lever 15 to provide a right angularly extending arm 30, which is formed relatively long and provided with suitable graduations 31 with which is adapted to coöperate the sliding weight 32, the purpose of which will be hereinafter more fully described. The levers 17 and 18 are identically constructed with the levers 15 and 16 and each of the same is provided with the inwardly extending feet 33 25 for engaging one of the bearings of the rolls of the lowermost pairs and have their upper ends provided with right angular arms 34, which are suitably graduated and receive the sliding weights 35.

35 Heretofore there has been no way to tell the exact pressure which is being applied to the rolls and as the pressure has much to do with regulating the amount of tin metal coating on a sheet of metal, considerable 40 difficulty has been experienced in coating sheet metal with the correct amount of tin. By graduating the arms and moving the weight, the exact amount of pressure upon the rolls can be determined, and thus the 45 exact amount of tin coating on the sheet metal may be regulated.

The rolls are connected together at one end by oblique gears 36, which take away the vibration or uneven pressure from the 50 plate, as it passes through the rolls, which cannot be obtained with the ordinary spur gears now in vogue.

In Fig. 3 is shown a modified form in which the V-toothed gearings are used and

it has been found that this gearing also 55 relieves uneven pressure on the plate and also vibration.

The opposite ends of certain of the rolls are provided with the relatively large drive gears 37 which are provided with either the 60 oblique or V-teeth as may be desired.

In practice, I have found that the form of my invention illustrated in the accompanying drawings and referred to in the above description, as the preferred embodiment, is the most efficient and practical; yet realizing the conditions concurrent with the adoption of my device will necessarily vary, I desire to emphasize that various minor changes in details of construction, proportion and arrangement of parts may be resorted to, when required without sacrificing any of the advantages of my invention as set forth.

What I claim as new is:

1. In a tinning machine, a frame, bearings 75 slidably mounted in the frame, rolls carried by said bearings, pivoted levers arranged to engage the bearings, and weights adjustably carried by the levers whereby the pressure on said bearings can be regulated.

2. In a tinning machine, a roll carrying frame including end plates, bearings slidably carried by the end plates, rolls journaled in the bearings, levers pivoted intermediate their ends and arranged to engage the bearings, said levers having right angularly extending arms formed on the upper ends thereof extending in a direction away from said rolls, and weights slidably mounted on the arms, whereby the pressure on said 85 bearings can be regulated.

3. In a tinning machine, a roll carrying frame having slots formed therein, bearings slidably mounted in the slots, rolls journaled in said bearings, levers pivotally carried by the end plates and arranged to engage the bearings, angularly extending ends formed on said levers, said ends being graduated, and sliding weights mounted on 95 said ends, as and for the purpose specified.

In testimony whereof I affix my signature in presence of two witnesses.

ROBERT L. COVINGTON.
